UNITED STATES PATENT OFFICE.

JAMES O. H. CAZENOVE, OF NEW YORK, N. Y.

MIXER.

Application filed February 27, 1922. Serial No. 539,592.

To all whom it may concern:

Be it known that I, JAMES O. H. CAZENOVE, a citizen of the United States, and a resident of New York, in the county of New York and State of New York, have invented certain new and useful Improvements in Mixers, of which the following, taken in connection with the accompanying drawings, is a specification.

10 This invention relates to mixers and more particularly to mixers of the egg beater type having rotatable beater blades.

It has been found by experimenting that various substances such as eggs, dressings, and other liquids which require considerable "beating" or aerating for proper mixing, may be more thoroughly mixed and in less time if the mixing means be periodically reversed. As it is obviously unhandy for an operator to periodically reverse the rotatory movement of his hand, it is an object of this invention to provide a mixer which will periodically reverse the mixing means functioning in the liquid while the operator actuates the operating means continuously in a single direction. Another object is the provision of a simple, cheap and highly efficient mixer applicable to many uses. Other objects will appear as the description proceeds.

The invention will be best understood from a consideration of the following detailed description taken in connection with the accompanying drawings forming part 35 of this specification and in which similar reference numerals refer to similar parts; it being understood, however, that the invention is not confined to any strict conformity with the showing in the drawings, but may be changed and modified so long as such changes and modifications mark no material departure from the salient features of the invention as expressed in the appended claims.

40 In the drawings:—

Figure 1 is a side elevation of the device embodying the invention, and showing a portion of the supporting frame broken away to expose the operating mechanism,

50 Fig. 2 is a vertical sectional elevation taken on the line 2—2, of Fig. 1,

Fig. 3 is a perspective view of a detail of the operating mechanism.

Referring in detail to the drawings, the mixer consists of a supporting frame, preferably constructed of sheet metal, compris-

ing in its simplest form a handle 1, a stem 2 and two parallel depending supporting brackets 3 and 4, all struck up from a single strip of metal preferably in the form as illustrated in Figs. 1 and 2, the parts forming the stem 2 being riveted together as at 5. The lower part of bracket 4 is bent at right angles to form a horizontal apertured extension 4^a which is rigidly connected to the lower end of bracket 3, and which serves to maintain the two brackets in parallel relation.

An operating crank 6 is provided with a horizontal shaft 7 which is both rotatable 70 and laterally slidable in bearings 8 and 9 mounted respectively in brackets 3 and 4.

Bevel gears 10 and 11 are rotatably mounted on the periphery of the bearings 8 and 9, respectively, within the space enclosed by the brackets, and are adapted to mesh with the opposite sides of a bevel pinion 12, the latter being rotatably mounted above the horizontal bracket extension 4^a on one end of the beater blade supporting rod 13. The spur gears 14 and 15 and associated beater blades 16 and 17 are mounted on the rod 13 in the usual way in this form of mixer, so that it is thought that further detailed description will be unnecessary.

Bevel gear 11 is provided with a series of radial teeth (see Fig. 1) or what may be designated a circular rack 19 which is formed on the inner face of said gear, that is, on the face which carries the bevel teeth. This rack 80 is positioned intermediate the axis and circumference of the gear face. Gear 10 is similarly provided with a circular rack 18, Fig. 2. After the gears 10 and 11 are in operative position in the supporting frame, the respective racks are diametrically opposite and face toward each other.

A clutch bar 20 is rigidly secured to the shaft 7 of the crank 6 midway between the bearings 8 and 9 as by the rivet 21. The opposite faces of this bar are provided with two integral teeth 22, 22^a and 23, 23^a, respectively; teeth 22 and 22^a being located adjacent one end of the bar, and teeth 23 and 23^a, adjacent the opposite end, as clearly shown in Fig. 3. The rack-engaging faces of all of the above teeth are preferably in the same vertical plane as the axis of shaft 7 which is at right angles to the sides of bar 20.

To operate the mixer, the operating crank 6 is moved laterally in bearings 8 and 9 to

the position shown in solid lines in Fig. 2, which movement causes the teeth 22^a and 23^a of bar 20 to mesh with certain teeth in the circular rack 19 on the gear 11. If crank 6 is now turned in a clockwise direction, bar 29 and gear 11 will be rotated in unison in the same direction causing pinion 12, spur gear 15 and the beater blades 17 to rotate at a more rapid rate to the right, and consequently, spur gear 14 and blades 16 to the left. If, however, crank 6 is moved to the position as indicated by the dotted lines in Fig. 2, the teeth 22^a and 23^a will disengage rack 19 and teeth 22 and 23 will mesh with certain teeth of rack 18. Since crank 6 is still being rotated in a clockwise direction, gear 10 will rotate in unison therewith, and, being in mesh with the opposite side of pinion 12, will cause the latter together with its associated beater blades to reverse its direction of rotation.

Thus it will be apparent that a periodic reversal in the direction of rotation may be imparted to the beater blades while turning the crank always in the same direction simply by sliding the crank arm in the bearings 8 and 9 toward or away from the frame a small predetermined distance.

I claim:—

- 30 1. In a mixer having rotatable mixing means, manually-operated means adapted to rotate said mixing means in either direction at the option of the operator of said manually-operated means.
- 35 2. In a mixer having mixing means including beater blades, manually-operated means adapted to rotate said mixing means in either direction at the option of the operator of the manually-operated means.
- 40 3. In a mixer having mixing means, means connecting said mixing means for rotation in

one direction, means connecting said mixing means for rotation in the opposite direction, and manually-operated means adapted to actuate either of said connecting means at the option of the operator thereof.

4. In a device of the class described, rotatable mixing means, gear means adapted to rotate said mixing means in one direction, other gear means adapted to rotate said means in the opposite direction, and operating means adapted to selectively engage either of said gear means.

5. In a device of the class described, a plurality of rotatable mixers, a bevel pinion connected thereto, a pair of bevel gears meshing continuously on opposite sides of said pinion, a crank adapted for rotation in one direction, means rigidly secured to said crank and adapted to engage means on either of the bevel gears whereby the engaged gear will be rotated in unison with the crank, and supporting means for the above-named mechanism.

6. In a device of the class described, a frame, a plurality of beater blades rotatably mounted thereon, a bevel pinion rigidly connected to one of the beater blades, a pair of horizontally aligned bearings mounted in said frame, a crank rotatably and slidably mounted in said bearings, gear means rotatably mounted on the periphery of said bearings, means connecting both of said gear means to said beater blades, and means connecting either of said gear means to said crank by a sliding movement of the crank in the bearings.

Signed at New York in the county and State of New York this 29th day of January, 1922.

JAMES O. H. CAZENOVE.
